(57) CLAIM

The ornamental design for a sandal, as shown and described.

DESCRIPTION

FIG. 1 is a perspective view of the sandal;

FIG. 2 is a front elevational view of the sandal;

FIG. 3 is a rear elevational view of the sandal;

FIG. 4 is a right side view of the sandal;

FIG. 5 is a left side view of the sandal;

FIG. 6 is a top down view of the sandal; and,

FIG. 7 is a bottom up side view of the sandal.

The broken lines of the sandal form no part of the claimed design.
